[57] CLAIM

The ornamental design for a carpet extractor lower portion, as shown and described.

DESCRIPTION

FIG. 1 is a perspective view showing a first embodiment of our new ornamental design for a carpet extractor lower portion;

FIG. 2 is a top elevational view thereof;

FIG. 3 is a front elevational view thereof;

FIG. 4 is a left side elevational view thereof, the right side being a mirror image thereof;

FIG. 5 is a rear plan view thereof;

FIG. 6, is a bottom elevational view thereof;

FIG. 7 is a perspective view showing a second embodiment of our new ornamental design for a carpet extractor lower portion;

FIG. 8 is a top elevational view thereof;

FIG. 9 is a front elevational view thereof, the right side being a mirror image thereof; and,

FIG. 10 is a left side elevational view thereof, the right side being a mirror image thereof, the rear view being the same as shown in FIG. 5 and the bottom view being the same as shown in FIG. 6.

The details shown in broken lines in FIGS. 1, 2, 5, 6, 7, and 8 are shown for illustrative purposes only and form no part of the claimed design.
